FLUFFING MACHINE

Fred B. Hirsch, East Providence, R. I.

Application April 25, 1938, Serial No. 203,979

2 Claims.

(Cl. 26—29)

My present invention relates to the textile art, and has particular reference to a fluffing machine for fluffing material having raised surface designs.

5 It is the principal object of my invention to provide a machine having means for subjecting textile material having raised surface designs to a fluffing action.

It is another object of my invention to fluff 10 the threads of raised surface dots and to bring them together in fluffed condition so as to maintain and enhance the raised appearance of the dots.

A further object of my invention is to provide 15 a fluffing machine which can be positioned in the path of travel of textile material undergoing processing, whereby separate handling and loss of manufacturing time is eliminated.

With the above and other objects and advan- 20 tageous features in view, the invention consists of a novel arrangement of parts and a novel method of fluffing more fully disclosed in the detailed description following, in conjunction with the accompanying drawings, and more 25 specifically defined in the claims appended thereto.

In the drawings:

Fig. 1 is a plan view, partly broken away, of an 30 illustrative embodiment of my invention;

Fig. 2 is a side elevation thereof;

Fig. 3 is a fragmentary detail of a section of cloth having a raised dot design; and

Fig. 4 is an enlarged sectional view of the fluffed dots.

35 It has been found desirable to mechanically fluff raised designs in textile materials, by subjecting a strip of textile material to brushes which are arranged to subject the raised designs to alternate brushings in opposite directions, 40 whereby the raised designs, such as for instance polka dots, are brushed to bring the individual threads out from the textile base, in a compact mass. To this end, I have devised an arrangement for subjecting each portion of the surface 45 of a traveling textile strip to alternate brushings in directions across the direction of movement of the textile strip.

Referring to the drawings, the fluffing machine includes a frame 10 comprising two spaced 50 standards 11, the frame and standards supporting a power driven rotatable brush roller 12, see Fig. 2, which is spaced forwardly of the frame, a guide roll 13, a power driven spreader roller 14, a guide roll 15 which is mounted in an ad- 55 justable support 16, a fixed spreader bar 17, an

adjustable guide bar 18 which is mounted in a housing 19 for vertical and horizontal adjustment, a second fixed spreader bar 20, a second guide roll 21 which is mounted in an adjustable support 22, and an exit power driven spreader 5 roll 23.

A plurality of rotary disk brushes 24 are rotatably mounted on cross bars 25 which support the fixed spreader bars 17 and 20, each having pulleys 26, whereby an endless belt 27, preferably 10 of V shape, rotates the pulleys, and therefore the rotary brushes, in opposed relation.

Referring now to Fig. 2, a textile cloth A, having a raised design, is passed from the processing apparatus or the like under the revolving brush 12, with the raised design towards the revolving brush, whereby foreign substances are brushed off and the raised design receives a preliminary brushing to loosen the threads or fibres. The cloth travels over the guide roll 13 to the spreader roller 14, where wrinkles are removed by the spreading action, and then passes over the adjustable guide roll 15, which is set so as to properly engage the raised design with the revolving brushes 24.

The cloth, which is again smoothed by the spreader bar 17, is again brushed, again smoothed, again brushed, and finally smoothed and spread, and passes on to a starching machine, if desired, and to the usual tentering 30 machine.

The revolving brushes 24, see Fig. 1, rotate in opposite directions, due to the use of the flexible V belt, and the raised designs on the cloth are thus subjected to lateral brushings in both directions to the path of travel, as well as to brushings along the path of travel and in opposed relation thereto. The fibres or threads of the raised designs are thus bunched and compacted while they are being brushed out, so that the final effect is to bring the raised design into sharp outline and sharp relief; polka dots, for example, become upstanding fluffed out tufts, the resulting cloth being very attractive in appearance.

45 Since the brushing is accomplished during travel of the cloth, no increase in processing time results, and the fluffing is accomplished with a minimum of supervision and at a very low expense.

50 Although I have described the apparatus as particularly suitable for brushing cloth having raised designs, the apparatus may be used for other textile brushings and processes, and may be changed for such purposes, without departing 55

from the spirit and the scope of the invention as defined in the appended claims.

I claim:

- 5 1. In a fluffing machine, a frame, a series of rotatable brushing disks mounted in transverse alignment on said frame, a second series of rotatable brushing disks mounted on said frame in spaced parallel alignment to said first series, the disks of said second series having their axes of rotation in intermediate relation to the axes of rotation of the disks of the first series, guide rod elements for guiding a strip of textile material successively into brushing contact with said disks, means for moving the strip of textile material across said disks, and means for rotating said disks to alternately brush the textile material surface in opposite directions.
- 10 10 15 2. In a fluffing machine, a frame, a series of

rotatable brushing disks mounted in transverse alignment on said frame, a second series of rotatable brushing disks mounted on said frame in spaced parallel alignment to said first series, the disks of said second series having their axes 5 of rotation in intermediate relation to the axes of rotation of the disks of the first series, guide rod elements for guiding a strip of textile material successively into brushing contact with said disks, means for moving the strip of textile material across said disks, and means for rotating said disks in the same direction to alternately brush the textile material in opposite directions.
